UNITED STATES PATENT OFFICE.

HENRY C. MERCER, OF DOYLESTOWN, PENNSYLVANIA.

PROCESS OF PRODUCING PICTURES OR DESIGNS.

SPECIFICATION forming part of Letter Patent No. 784,169, dated March 7, 1905.

Application filed September 22, 1904. Serial No. 225,467.

To all whom it may concern:

Be it known that I, HENRY C. MERCER, a citizen of the United States, residing at Doylestown, in the county of Bucks and State of Pennsylvania, have invented new and useful Improvements in Processes of Producing Pictures or Designs, of which the following is a specification.

My invention pertains to the making of pictures, designs, and the like; and, broadly stated, it contemplates a process whereby a person is enabled to multiply a picture, design, or analogous artistic creation, either original or otherwise, and display in each production artistic skill, so that each possesses individuality and has the nature of an original rather than that of a mere copy or print.

Primarily the process is designed to enable an artist to quickly and cheaply create a picture, design, or the like, which he conceives in somewhat the same manner as in wood-cutting as originally practiced, and multiply the picture or design and display in each production evidences of his artistic ability.

With the foregoing in mind the invention will be fully understood from the following description and claims when taken in connection with the accompanying drawings, forming part of this specification, in which—

Figure 1 is a view of a copy of a picture produced in accordance with my invention, and Figs. 2 to 9 are sectional views illustrative of the steps included in my novel process.

Similar letters of reference designate corresponding parts in all of the views of the drawings.

In carrying out my process I first draw the outlines of a picture, design, or the like, and, where desired, other lines—such, for instance, as those to indicate shading or middle values—upon a sheet of paper, textile fabric, or other suitable material. I then lay the sheet back down upon a flat slab A, Fig. 2, of clay, modeler's wax, casting-sand, or other material adapted to be impressed and go over the lines—*i. e.*, both outlines and the lines to indicate shading or middle values—with a pencil or other instrument, so that upon the removal of the sheet the lines appear on the face of the slab A. I then through the medium of a chisel,

knife, or other means form channels *a a'* of V shape or other shape in cross-section in the face of the slab, the channels *a* corresponding to the lines of the picture or design, as shown in Fig. 3—*i. e.*, the bold lines or outlines—and the channels *a'* corresponding to the finer lines indicating shading or middle values. I next pour plaster-of-paris or other material adapted to be cast or molded on the slab A, Fig. 4, and by so doing produce a type B, Fig. 9, having raised portions *b*, designed to reproduce the outlines of the picture or design, and the raised portions *b'*, designed to reproduce the shade or value indicating lines of the picture or design in the manner hereinafter described. I then invert the type B and, if necessary, suitably reduce its raised portions *b b'* to a common height, after which I lay a thin slab C, Fig. 5, of plastic or other material, on the type B and press said slab down into the depressions of the said type. Then I turn the type B and the slab C over, so that the type B is uppermost, as shown in Fig. 6, remove the type B from the slab, and cut entirely through the slab where depressions are formed by the raised portion *b* of the type, and by so doing divide the slab into a plurality of blocks or subtypes D, Fig. 7, each of which blocks or subtypes corresponds in shape and size to one of the depressions of the type B, the walls of which are formed by the raised portions *b* of said type. I do not, however, cut through the slab where depressions are formed by the raised portions *b'* of the type, the latter depressions (lettered *b'* in Fig. 7) being designed to serve as sockets for the raised portions *b'* of the type when the subtypes are in use, as presently described. Subsequent to the formation of the subtypes D, I may in order to expeditiously assemble the said subtypes D in proper relation to the type B place the said type B over the subtypes D and then turn the whole over, so that the type B is lowermost and each subtype rests in its respective depression of the type and on any raised portions *b'* that may occur therein and extends above the raised portions *b*, defining the areas of the depressions. I desire it understood, however, that the subtypes may be assembled in proper relation to each other in

- any other manner compatible with the purposes of my invention.
- When made of clay or analogous material, the blocks or subtypes D will in drying shrink 5 on all sides equally, so as to afford spaces between them for the lines of the picture or design to be produced through the medium of the type B in the manner hereinafter described. Said subtypes D when made of clay 10 or analogous material may be and preferably are burned to render them hard and durable. It is not essential, however, that they be hard, since they are not subjected to pressure, as will be hereinafter understood.
- 15 It will be readily appreciated that in the manner described the subtypes D corresponding in shape to the depressions defined by the raised portions *b* of the type B may be very quickly and easily produced.
- 20 In the practice of my process the artist first conceives the picture, design, or the like and then draws the same upon a sheet of suitable material, and then in the manner described he provides the means—*i. e.*, the type B and 25 the subtypes D—for enabling him to quickly and easily produce a multiplicity of his creations. In accomplishing this latter either the color areas or the outlines and other lines may be produced first, as described. I will, 30 however, for the sake of convenience describe the process by which the color areas and the outlines and other lines—*i. e.*, the lines to indicate shading or middle values—are produced in the order named.
- 35 To produce the picture upon a sheet of paper or other material, the type B is fastened on a table, and the subtype or subtypes D, corresponding to the divisions of the picture which are to be colored, say, green, are alone 40 placed in said type B. The sheet of paper or other material (indicated by E in Fig. 8) is then placed on the form which the type B and subtypes D constitute and is registered by any of the devices known in the art of printing, 45 after which the artist grasps an applier of wood-pulp, asbestos, or other suitable material, places or takes up green pigment on the same, and rubs the applier over the face or upper side of the sheet. When this is done, 50 the subtypes D in the type B effect the application of the green pigment to the portions of the upper side of the sheet exactly above said subtypes; but no other portion or portions of the sheet take the green pigment. The sheet 55 is then removed and other sheets are placed on the form and removed therefrom in succession, green pigment being applied to each sheet while the same is on the form in the same manner that it is applied to the first 60 sheet. The subtypes for the divisions of the picture to be colored green are then removed from the type B, and other subtypes corresponding to the divisions of the picture to be colored, say, brown, are then placed in their 65 respective depressions of the type B. The sheets are then placed on and removed from the form in succession, brown pigment being rubbed on the face of each sheet while it is on the form, when the portions of the sheet exactly above the subtypes, but no other portions, will take the brown pigment. This operation is repeated until all of the colors included in the pictures are applied to the faces or upper sides of all of the sheets, when the sheets are ready to receive the lines of the 75 pictures. To produce the lines on the sheets, all of the subtypes D are removed from the type B, and the sheets are laid on and removed from the type B in succession, black pigment, for instance, being rubbed over the 80 face of each sheet while it is on the type B. When this is done, it will be observed that the sheets will take the black pigment at points over the raised portions *b* of the type B to form the outlines of the pictures and at 85 points over the raised portions *b'* of said type B to form the shading or middle values in the areas defined by the outlines, the black being disposed over the colors in said areas and varying the tones of the colors. In this way 90 it will be observed that the colored divisions of the picture will be separated and shaded and the pictures completed.
- In the use of the subtypes D in the type B in the manner before described it will be understood that the subtypes project above the raised portions *b* of the type and rest over the raised portions *b'* thereof, so that while the subtypes are in use the said raised portions *b* and *b'* are idle. 95
- In some cases the subtypes D may be made to fit closely together, in which event there will be no outlines or stripes between the colored divisions, and hence no necessity of placing the sheets on the type B to receive the 100 outlines of the picture or design after all of the divisions of the picture are colored. Again, the subtypes may be made to fit so closely as to cause the different colors to overlap each other, which in some, but not all pictures or 105 designs, will add to the beauty thereof. In either case the outlines of the picture or design may be produced or not on the sheets, as desired, without involving departure from the scope of my invention. I also desire it understood that when it is not desired to shade with lines the raised portions *b'* of the type B 110 may be omitted. In this event by rubbing the colored divisions on their respective subtypes the tints of the colors may be varied and 115 beautiful effects produced.
- In my novel process it will be observed that the form—*i. e.*, the type B and subtypes D—is the creation of the artist and that in the production of the pictures the same appear on 120 the sheets immediately under the eye of the artist, and because of this and the fact that the artist applies the colors by hand the artist is enabled to display his ability in the production of each picture; also, the artist can super- 125 130

impose various colors upon others, and thereby obtain a great variety of color tones and enhance the beauty of the picture. From this it follows that my process involves a combination of free-hand painting with printing, the major portion of the work—*i.e.*, the drudgery—being accomplished by the apparatus and the variation in tone, finishing, or master touches, &c., by the hand of the artist.

10 The mode described of producing the type and subtypes is very simple and expeditious and is materially advantageous for such reason. I do not desire, however, to be understood as confining myself to such mode, as the 15 type and subtypes may be produced in any manner compatible with the purposes of my invention without involving a departure from the scope of my invention.

In lieu of forming the type B with the raised 20 portions b' for indicating shade-lines the subtypes may be cast with lines for shading upon them, in which event in printing these lines will take the special color of the pigment that the subtypes take, while other lines and outlines in the picture may be of another color or colors.

When desired, the type B and the subtypes 25 D may be used in a press, ink being applied to the faces of the subtypes, also ink or paint 30 may be applied to the faces of the subtypes, the sheet of paper, or other material placed on the subtypes, and a pad rubbed over the sheet after the Japanese mode of printing without 35 involving departure from the scope of my invention.

Having described my invention, what I claim, and desire to secure by Letters Patent, is—

1. The process of producing pictures or 40 signs, which consists in providing the surface of a slab with a picture or design, forming depressions in the slab along the lines of the picture or design, molding a type on the slab, whereby the type is provided with raised and 45 depressed portions, forming subtypes corresponding in shape to the depressions of the type, placing one or more of said subtypes in the corresponding depression or depressions of the type, placing a sheet of material 50 over the form, and applying pigment, ink or the like to the portion or portions of the sheet over the subtype or subtypes.

2. The process of producing pictures or 55 signs, which consists in providing the surface of a slab with a picture or design, forming depressions in the slab along the lines of the picture or design, molding a type on the slab, whereby the type is provided with raised portions and depressions, forming subtypes corresponding in shape to the depressions of the type, placing one or more of said subtypes in the corresponding depression or depressions of the type, placing a sheet of material over the form, applying pigment, ink or the like 60 to the portion or portions of the sheet over the

subtype or subtypes, removing the subtype or subtypes from the type, placing the sheet over the said type, and applying pigment, ink or the like to the portions of the sheet over the raised portions of the type.

3. The process of producing pictures or designs, which consists in providing the surface of a slab with a picture or design, forming depressions in the slab along the lines of the picture or design, molding a type on the slab, 70 whereby the type is provided with raised portions and depressions, forming subtypes corresponding in shape to the depressions of the type, placing one or more of said subtypes in the corresponding depression or depressions 75 of the type, placing a sheet of material over the form, and applying pigment to the face or exposed side of the sheet, whereby the portion or portions of the sheet above the subtype or subtypes will alone take the pigment.

4. The process of producing pictures or designs, which consists in providing the surface of a slab with a picture or design, forming depressions in the slab along the lines of the picture or design, molding a type on the slab, 80 whereby the type is provided with raised portions and depressions, forming subtypes corresponding in shape to the depressions of the type, placing one or more of said subtypes in the corresponding depression or depressions 85 of the type, placing a sheet of material over the form, applying pigment to the face or exposed side of the sheet, whereby the portion or portions of the sheet above the subtype or subtypes will alone take the pigment, removing the subtype or subtypes from the type, 90 placing the sheet over the type, and applying pigment to the face or exposed side of the sheet, whereby the portion or portions of the sheet above the subtype or subtypes will alone take the pigment, removing 95 the subtype or subtypes from the type, placing the sheet over the type, and applying pigment to the face or exposed side of the sheet, whereby the portion or portions of the sheet above the subtype or subtypes will alone take the pigment, removing 100 the subtype or subtypes from the type, placing the sheet over the type, and applying pigment to the face or exposed side of the sheet, whereby the portion or portions of the sheet above the subtype or subtypes will alone take the pigment.

5. The process of producing pictures or designs, which consists in providing the surface of a slab with a picture or design, forming depressions in the slab along the lines of the picture or design, molding a type on the slab, whereby the type is provided with raised portions and depressions, molding subtypes on the type, separating the subtypes, placing one or more of said subtypes in the corresponding 105 depression or depressions of the type, placing a sheet of material over the form, and applying pigment, ink or the like to the portion or portions of the sheet over the subtype or subtypes.

6. The process of producing pictures or designs, which consists in providing the surface of a slab with a picture or design, forming depressions in the slab along the lines of the picture or design, molding a type on the slab, 110 whereby the type is provided with raised portions and depressions, molding subtypes on the type, separating the subtypes, placing one or more of said subtypes in the corresponding 115 depression or depressions of the type, placing a sheet of material over the form, and applying pigment, ink or the like to the portion or portions of the sheet over the subtype or subtypes.

a sheet of material over the form, applying pigment, ink or the like to the portion or portions of the sheet over the subtype or subtypes, removing the subtype or subtypes from the type, placing the sheet over the said type, and applying pigment, ink or the like to the portions of the sheet over the raised portions of the type.

7. The process of producing pictures or designs, which consists in making a type having raised portions and depressions, making subtypes corresponding in shape to the depressions of the type, placing one or more of said subtypes in the corresponding depression or depressions of the type, placing a sheet of material over the form, and applying pigment, ink or the like to the portion or portions of the sheet over the subtype or subtypes.

8. The process of producing pictures or designs, which consists in making a type having raised portions and depressed portions, making subtypes corresponding in shape to the depressions of the type, placing one or more of said subtypes in the corresponding depression or depressions of the type, placing a sheet of material over the form, applying pigment, ink or the like to the portion or portions of the sheet over the subtype or subtypes, removing the subtype or subtypes from the type, placing the sheet over the said type, and applying pigment, ink or the like to the portions of the sheet over the raised portions of the type.

9. The process of producing pictures or designs, which consists in placing a sheet of material over subtypes and applying pigment to the exposed surface of the sheet by rubbing the pigment over the portions of the sheet over said subtypes, and placing the sheet over

a type having raised portions and depressions and applying pigment to the exposed surface of the sheet by rubbing pigment over the portions of the sheet over the raised portions of the type.

10. The process of producing pictures or designs, which consists in making a type having raised portions *b* and *b'* and depressed portions, making subtypes corresponding in shape to the depressions of the type, placing one or more of said subtypes in the corresponding depression or depressions of the type, placing a sheet of material over the form, applying pigment, ink or the like to the portion or portions of the sheet over the subtype or subtypes, removing the subtype or subtypes from the type, placing the sheet over the said type, and applying pigment, ink or the like to the portions of the sheet over the raised portions of the type.

11. The process of producing pictures or designs, which consists in making a type having raised portions and depressions, making subtypes corresponding in shape to the depressions of the type, placing one or more of said subtypes in the corresponding depression or depressions of the type, placing a sheet of material over the form, utilizing either the type or one or more of the subtypes to form shading lines, and applying pigment, ink or the like to the portion or portions of the sheet over the subtype or subtypes.

In testimony whereof I have hereunto set my hand in presence of two subscribing witnesses.

HENRY C. MERCER.
